UNITED STATES PATENT OFFICE.

CHARLES F. BINGHAM, OF BUFFALO, NEW YORK, ASSIGNOR TO
WILLIAM P. TAYLOR.

BRAKE-SHOE.

No. 802,350.

Specification of Letters Patent.

Patented Oct. 17, 1905.

Application filed May 25, 1905. Serial No. 262,192.

To all whom it may concern:

Be it known that I, CHARLES F. BINGHAM, a citizen of the United States, residing at Buffalo, in the county of Erie and State of New York, have invented certain new and useful Improvements in Brake-Shoes, of which the following is a specification.

This invention relates to an improved reinforced railway brake-shoe of that class which 10 consists of a cast body and one or more reinforcements which are secured to the body during the casting thereof.

One of the features of the invention resides in a novel form of plate-like reinforcement 15 which is provided with one or more openings or slots in which portions of the cast body interlock.

Another feature has reference to one or 20 more projecting portions which are formed by the stamping of the openings or slots in the plate-reinforcement which extend at an angle therefrom and constitute integral anchoring elements for the said plate-reinforcement.

25 The object of the invention is to produce a rigid and mutual interlocking of the reinforcement and metal body.

This invention also relates to certain details of construction, all of which will be fully and 30 clearly hereinafter described and claimed, reference being had to the accompanying drawings, in which a preferred adaptation of the invention is shown.

Figure 1 is a vertical longitudinal section 35 through the improved brake-shoe on line *a a*, Fig. 3. Fig. 2 is a longitudinal section through the improved brake-shoe cut on the curved line *b b*, Fig. 1, concentric with the curved braking-surface of the shoe. Fig. 3 is an 40 enlarged transverse section through the improved brake-shoe on line *c c*, Fig. 1. Fig. 4 is an enlarged transverse section on line *d d*, Fig. 1. Fig. 5 is a face view of the improved form of reinforcement. Fig. 6 is an edge 45 view of the improved form of reinforcement.

In referring to the drawings for the details of construction, like numerals designate like parts.

The preferred type of this improved brake- 50 shoe consists of a cast body and one or more plate-like reinforcements which are secured in said body during the casting thereof, and are provided with one or more openings or slots in which portions of the molten metal

of the shoe-body run to rigidly interlock the 55 brake-shoe and reinforcement together. Instead of entirely severing the metal pieces which are stamped out to provide the openings or slots, they may be cut partially and then bent outwardly to leave the required slots or 60 openings, and also form projecting parts which serve to more securely interlock the reinforcement in place in the cast body.

The preferred adaptation of this improved 65 brake-shoe comprises a cast body 1 of the usual shape and two reinforcements 2. These reinforcements are of similar construction, and each consists of fairly narrow strips of sheet or wrought metal curved to the curve of the shoe-body and provided with a plurality of longitudinally - elongated or oblong 70 openings or slots 3, which are approximately centrally located between the two side edges of the reinforcement and extend in longitudinal rows. The slots 3 are preferably formed 75 with rounded ends, so that no sharp corners are presented to the interfitting locking portion 4 of the cast body. The purpose of these slots is not only to produce openings or breaks in the surface of the reinforcements in which 80 the cast metal of the body will interlock, but also to afford means whereby the plates are retained and supported in place during the cooling of the shoe after casting the body and to reduce the extent of surface of the reinforcement without lessening its width. In 85 stamping the slots the metal is cut at the ends and one side only, and is bent outwardly to form the projecting parts 5, which serve to additionally lock the reinforcement in the 90 body. The projecting parts 5 are bent vertically upward, and are embedded and locked in that portion of the cast body above the main body portion of the reinforcement, so that if the shoe-body is worn thin enough to 95 entirely expose the lower surface of the reinforcement and said reinforcement is loosened it will still be locked to the remaining portion 100 of the cast body by the projecting parts and cannot drop off. The projections 5 are bent 100 alternately from opposite sides of the openings, so that they are arranged in staggered relation. By this means each plate has a central longitudinal row of openings and two longitudinal series of upwardly-extending projections, each series of projections being approximately half as large in number as the 105 openings, and each projection of each series

extending from one side of each alternate opening. The slots 4 and parts 5 are formed by making a series of angular or E-like cuts in the plate-body and bending the parts partially inclosed within the E-like cuts outwardly.

The great advantage of this improvement is that the slotted reinforcement is of the same even width throughout and is rigidly secured in and interlocked to the body by portions of the body itself, which fit into and lock in slots in the central portion of the reinforcements, whereby a mutual interlocking of the reinforcement and cast body is obtained, and the reinforcement is also additionally locked to the body by integral vertical projecting parts, which are formed of the portions cut and bent from the body of the reinforcement to provide the slots.

I claim as my invention—

1. A brake-shoe comprising a cast body and a plate-reinforcement embedded in said body having an opening or slot in which a portion of said body interlocks and the metal cut to form said opening or slot being bent vertically upward at one side of said opening or slot to form an upwardly-extending projection.

2. A brake-shoe comprising a cast body and a plate-reinforcement in said body having a plurality of equally-spaced openings or slots in a central longitudinal row in which portions of said body interlock.

3. A brake-shoe comprising a cast body and a plate reinforcement in said body having a slot in which a portion of said body interlocks: the ends of said slot being rounded and the sides being straight and the metal cut to form said slot being cut at the ends and one side only and being bent upon on the remaining side to form an integral projection.

4. A brake-shoe comprising a cast body and a plurality of parallel reinforcing plates of fairly narrow width each having a plurality of oblong slots in which portions of the body interlock.

5. A reinforcement for brake-shoes consisting of an elongated plate having an open-

ing and an integral upwardly-extending projection formed by bending that portion of said plate cut to provide the opening.

6. A reinforcement for brake-shoes consisting of an elongated plate having a plurality of angular cuts at regular intervals with the parts adjacent to said cuts bent outwardly to form projecting portions and also leave openings through the plate.

7. A brake-shoe comprising a cast body and a plate-reinforcement in said body having an opening or slot in which a portion of said body interlocks and a projection extending vertically from one side of said opening or slot and embedded in said cast body.

8. A brake-shoe comprising a cast body and a plate-reinforcement in said body having an opening or slot in which a portion of said body interlocks, an integral upwardly-extending projection embedded in said cast body above the main portion of said reinforcement.

9. A brake-shoe comprising a cast body and a plate-reinforcement in said body having an interior part partially cut and bent to form a projecting upwardly-extending locking part and also provide an opening in which a portion of the cast body interlocks.

10. A brake-shoe comprising a cast body and a plate-reinforcement in said body having separated interior parts partially cut and bent to form upwardly-extending projecting locking parts and also provide openings in which portions of the cast body interlock.

11. A reinforcement for brake-shoes consisting of an elongated plate having a series of upwardly-extending projections arranged in staggered relation.

12. A reinforcement for brake-shoes consisting of an elongated plate having a series of openings in a longitudinal row and a series of upwardly-extending projections extending alternately from opposite sides of said openings.

CHARLES F. BINGHAM.
